CLAIM

The ornamental design for a “combined transmitter and receiver for a vehicle parking indicator sensor”, as shown and described.

DESCRIPTION

FIG. 1 is a front perspective view of a combined transmitter and receiver for a vehicle parking indicator sensor according to our design, wherein the connector between the sensor and the indicator shown by broken lines is not part of the claimed design;

FIG. 2 is a top plan view thereof;

FIG. 3 is a front elevational view thereof;

FIG. 4 is a right side elevational view, the left side being a mirror image of the right side elevational view;

FIG. 5 is a bottom plan view thereof;

FIG. 6 is a rear elevational view thereof; and,

FIG. 7 is a rear elevational view of an alternative embodiment thereof.
